(57) **CLAIM**

The ornamental design for a pet car seat strap, as shown and described.

DESCRIPTION

FIG. 1 is a perspective top view of a pet car seat strap showing our new design;

FIG. 2 is a back view thereof;

FIG. 3 is a right side view thereof;

FIG. 4 is a top view thereof; and,

FIG. 5 is a bottom view thereof.

The broken lines showing the pet car seat in the drawings depict environmental subject matter that forms no part of the claimed design.
